UNITED STATES PATENT OFFICE.

THOMAS P. KERSEY AND EDWIN W. LEACH, OF PULASKI, TENNESSEE.

THILL-COUPLING.

SPECIFICATION forming part of Letters Patent No. 602,989, dated April 26, 1898.

Application filed June 8, 1897. Serial No. 639,873. (No model.)

To all whom it may concern:

Be it known that we, THOMAS P. KERSEY and EDWIN W. LEACH, citizens of the United States, residing at Pulaski, in the county of 5 Giles and State of Tennessee, have invented a new and useful Thill-Coupling, of which the following is a specification.

The invention relates to improvements in thill-couplings.

10 The object of the present invention is to improve the construction of thill-couplings and to provide a simple, strong, and durable one which will enable poles and thills to be readily connected to and removed from a vehicle without necessitating the employment of a wrench or similar tool.

15 The invention consists in the construction and novel combination and arrangement of parts, as hereinafter fully described, illustrated in the accompanying drawings, and pointed out in the claim hereto appended.

20 In the drawings, Figure 1 is a perspective view of the thill-coupling constructed in accordance with this invention. Fig. 2 is a vertical longitudinal sectional view of the same. Fig. 3 is a horizontal sectional view. Fig. 4 is a detail perspective view of the axle-clip, the same being inverted to illustrate the manner of mounting the spring-catch on the same. 25 Fig. 5 is a detail perspective view of the coupling arm or frame. Fig. 6 is a detail perspective view of the spring-catch.

30 Like numerals of reference designate corresponding parts in the several figures of the drawings.

35 I designates an axle-clip provided with a forwardly-extending lug or enlargement 2, provided at opposite sides with vertical recesses 3 and having a dovetailed groove 4 in its front face. This lug or enlargement is 40 adapted to interlock with a coupling iron or frame 5, which is provided at its back with a central dovetailed arm 6 and a pair of rearwardly-extending side arms 7. The central 45 dovetailed arm 6 is adapted to fit snugly within the dovetailed groove 4 and tapers from its top to its bottom, and the side arms 7 are provided at their inner faces with vertical bosses having convex faces which conform 50 to the configuration of the side recesses 3. By this construction the frame is firmly inter-

locked with the enlargement of the clip and is readily coupled and uncoupled therefrom by slipping it downward on the same and lifting it vertically therefrom. 55

The coupling iron or frame is retained in engagement with the enlargement of the axle-clip by a spring-catch 9, provided with a beveled head, which forms a lower shoulder and which is adapted to project over the upper 60 face of the central arm 6 when the parts are coupled to retain them in such engagement. The head of the spring-catch is adapted to be readily pressed backward to release the coupling-frame, and the beveling of the head permits the spring-catch to engage the coupling iron or frame automatically in the coupling 65 of the parts. The spring-catch is provided with a T-shaped shank, arranged in a vertical recess 10 of the rear wall of the dovetailed 70 groove and in a transverse recess 11 of the bottom of the enlargement, which is provided with projecting lugs or flanges 12 for securing the arms of the shank in the bottom recess.

75 The coupling iron or frame is provided with forwardly-projecting ears 13, perforated to receive a transverse coupling-bolt 14, which connects a thill-iron 15 to the coupling iron or frame in the usual manner.

An antirattler-spring 16 is interposed between the eye of the thill-iron and the central portion of the coupling iron or frame and consists of a substantially U-shaped loop and a pair of arms connected with the sides of the loop by spring-coils. 85

The invention has the following advantages: The thill-coupling is simple, inexpensive, strong, and durable, and it will enable poles and thills to be readily attached to and removed from a vehicle without necessitating the employment of a wrench. It will also enable the operation of coupling and uncoupling to be performed with great rapidity, and it is especially advantageous in disconnecting the shafts or pole of a vehicle should a horse fall, and it will avoid all liability of a shaft being broken by stock contacting with it while one side is connected with the axle and the other side free. 90 95

100 What we claim is—

In a thill-coupling, the combination of an axle-clip having an enlargement provided at

its front with a tapering dovetailed groove and at its sides with grooves, a coupling-frame provided with a tapering arm interlocked with the dovetailed groove and supporting the coupling-frame, the latter being provided with rearwardly-extending side arms having bosses engaging the side grooves of the enlargement, and a spring-catch mounted on the enlargement and having its engaging portion at the top thereof in position to be automatically depressed by the dovetailed arm in as-

sembling the parts, substantially as and for the purpose described.

In testimony that we claim the foregoing as our own we have hereto affixed our signatures in the presence of two witnesses.

THOMAS P. KERSEY.
EDWIN W. LEACH.
